UNITED STATES PATENT OFFICE

LANCELOT MARTIN SIMPSON, OF LEEDS, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed May 12, 1928, Serial No. 277,188, and in Great Britain May 26, 1927.

The present invention relates to telephone systems and is more particularly concerned with what is known as routine testing apparatus, that is to say apparatus arranged to 5 produce automatically the actual conditions of use for each unit in turn of a large group of similar pieces of apparatus. The invention also is intended to be applied more particularly to the testing of apparatus which can 10 only be tested while it is not actually in use and must not be busied to its normal means of access in order that a test may take place. It is generally recognized nowadays that 15 routine testing is desirable, if not essential, particularly for complicated apparatus, in order that it may be possible to anticipate faults rather than correct them after they occur, and for the test to be effective it is 20 essential that every piece of apparatus shall be tested. This clearly presents a difficulty 25 in the above-mentioned circumstances, and it is the main object of the invention to deal with cases of this sort in a simple manner.

According to one feature of the invention, in an automatic testing arrangement for the routine testing of apparatus as used in telephone systems, in which idle pieces of similar apparatus are tested in turn until all have 30 been dealt with, if a piece of apparatus is seized for use while it is being tested, the operation of the testing equipment is suspended for an interval.

These features and others not specifically mentioned at this point will be better understood from the following description of one 35 method of carrying the invention into effect which should be taken in conjunction with the accompanying drawings. Clearly any routing arrangement will need to be specially 40 designed in view of the apparatus it is desired to test and the arrangement shown has been designed for the testing of key-sending 45 operators' positions of the type described in the Passmore application, Serial No. 752,138 filed Nov. 25, 1924. It will be recalled that in the arrangement disclosed in this specification, calls passed to a B operator over an order wire are set up on a single set of digit 50 keys the operation of which serves to control an impulse sender to send out the necessary

trains of impulses for operating automatic switches to connect with the wanted line. As a general rule the B operator will have 40 trunks incoming to her position, though in particular cases this number may be increased to 50. Moreover, in view of the fact 55 that the complete operation of an impulse sender takes several times as long as the setting of the digit keys, it is arranged that as many as four impulse senders can be associated with her position at a time in order that she may work continually at full speed, the impulse senders being accessible in common to a considerable number of operators. The testing of the complete apparatus falls 60 naturally into two parts, one comprising the testing of the actual impulse senders which may be done as described in British Patent No. 267606 and the other the testing of the junction relay sets and apparatus for associating impulse senders with the operator's key-set. A little consideration will show 65 that for a complete test to be carried out it is necessary to employ the apparatus at the operator's position used for associating an idle 70 impulse sender with that position, hence it follows that the test cannot be carried out while the position is in service.

Referring now to the accompanying drawings comprising Figs. 1-8, Figures 1 and 2 show the various controlling keys and a number of the associated relays; Figures 3 and 4 show a further group of the relays controlling the routiner; Figures 5 and 6 show the test switch TS, the release timing switch RS and the number-set-up switch NS, together with the fault indicating lamps for indicating the progress of a particular test; while Figures 7 and 8 show the distribution equipment by means of which connection is 80 made with each position in turn, and also with each junction in turn at a particular position. In order to facilitate the understanding of the circuit, the description will 85 be divided into two parts, firstly consideration of the arrangements by which connection is made in turn to the various positions and each junction at the position is tested, and secondly consideration of the actual tests 90 which are carried out on the junction and the 95 100

circuit arrangement by means of which they are applied.

Considering first, therefore, the distribution equipment in the arrangement shown, it is assumed that the test set is to serve for 60 operators' positions and that each position has 50 incoming junctions and means for associating four impulse senders with the position at a time. The position distribution equipment comprises a primary distributor PD from which access is had to three secondary distributors SD¹—SD³ of which only SD¹ and SD³ are shown (Fig. 7) since the circuits of SD² are similar. Preferably the contacts of the primary distributor PD are multiplied round the bank as shown so as to avoid unnecessary operation of the switch. Since it is not found possible to provide the secondary distributors with sufficient wipers for all the functions which they are required to perform, each one has associated with it an auxiliary secondary distributor of which only the auxiliary secondary distributor ASD¹ associated with the switch SD¹ is shown in Figure 8. Each secondary distributor is wired to have access to 20 operators' positions and when all the 20 have been tested or found busy, the primary distributor is advanced so as to connect up the succeeding secondary distributor. Associated with each position are a pair of junction distributors such as JD¹ and JD² (Fig. 8) which are given access to a maximum of 24 and 22 junctions respectively. Where the full 50 junctions are equipped, access is obtained to the last four over the first four contacts of the distributor JD¹, a suitable switching operation being performed to connect these junctions up in place of junctions 1—4 as will be described subsequently. The junction distributors are provided with a normal position in which the contacts are left dead and by this means the wipers of the junction distributors associated with all the positions may be multiplied together to the routine test set and the position distributors ensure that the junction distributors of only one position shall be operated at a time. It should be mentioned with reference to Figure 7 that the banks of wipers 618—620 of the secondary distributor SD³ are wired to the various junction distributors in the same manner as is indicated by the wiring of the first contacts in the banks of secondary distributor SD¹. The bank of wiper 617 is wired to the contacts of the associated position battery feed relays while that of wiper 621 is wired to the bank of the associated auxiliary secondary distributor ASD³. The switch SD² is wired similarly. As regards the auxiliary secondary distributor ASD¹, over wipers 639 and 640 of this switch access is had to the order wire leads of the various positions, while over wipers 641—644 connections are made to the four leads ex-

tending from the operators' keyset so that a test number may be set up from the routiner. Over wiper 645 circuits are completed for changing over from junctions 1—4 to junctions 47—50 where this is necessary. The other auxiliary secondary distributors are wired in a similar manner. The bank of wiper 625 of the junction distributor JD¹ is wired to the lamp leads of the various junctions, that of wiper 626 to the respective assignment leads and those of wipers 627 and 628 to the negative and positive trunk conductors respectively. The banks of the wipers such as 629 of all the junction distributors are commoned together and extend to indicating lamps such as 648 by means of which the attendant may see which junction is being dealt with at any time. The particular position being routined is indicated by the lighting of the corresponding lamp such as 608 connected to the banks of wipers 612 and 618. These lamps will flash as described subsequently when the associated position is being tested and will glow steadily when the routine indicating key is operated if the position has been tested or the busying key 609 is operated.

The operations involved in making a test will now be considered in detail. In order to set the routiner in operation, the attendant operates the start key SK whereupon a circuit is completed for relay 115. Relay 115 upon operating, at armature 116 prepares a circuit for the test relay 131, at armature 117 completes a circuit for the relay 119, and at armature 118 prepares the pulsing circuit to the first secondary distributor. Relay 119 now operates and at armature 120 opens the circuit of relay 280 which is normally energized in the following circuit: battery, relay 280, lead 407, normal contact and wiper 622 of the switch SD², normal contact and wiper of the switch SD² represented by the link 624, normal contact and wiper 616 of the switch SD¹, lead 18, armature 120 and its back contact to earth, and at the front contact of armature 120 extends earth over lead 26, wiper 603 of the primary distributor PD, lead 23, winding of relay 215 to battery so that relay 215 is operated and prepares circuits for the junction distributors and auxiliary secondary distributor and also for the relay 185. Furthermore, at armature 121 relay 119 prepares a circuit for stepping the junction distributors, and at armature 122 completes a circuit for relay 127 which extends as follows: battery, winding of magnet 507 of the switch TS, lead 439, armature 313 and its back contact, lead 441, interrupter contacts 508, wiper 506 and its normal contact, lead 93, winding of relay 127, armature 122 and its front contact, lead 43, back contact and armature 332 to earth. Relay 127 is operated at this time and at armature 128 opens a point in the locking circuit of relay 130

112, at armature 129 prepares circuits for relays 152 and 180 and at armature 130 closes the pulsing circuit of the secondary distributor. Relay 119 moreover at armature 123 opens the homing circuit of the primary distributor and provides a locking earth, at armature 124 prepares a circuit for stepping the primary distributor after each secondary distributor has rotated over all positions connected to it, at armature 126 opens an alarm circuit over lead 57 and at armature 125 connects earth to motor start lead 94 and opens normally closed circuit for relay 278 which extends as follows: battery, winding 5 of relay 278, lead 498, link 649 representing wipers and normal contacts of all the junction distributors not shown, normal contact and wiper 637, normal contact and wiper 630, lead 1, back contact and armature 125 to earth. Relay 278 now de-energizes thereby altering certain supervisory circuits as will be described subsequently. The pulsing circuit completed on the operation of relay 127 extends from earth, winding of relay 264, 20 armature 267 and its back contact, lead 47, armature 148 and its back contact, lead 61, back contact and armature 286, lead 62, armature 136 and its back contact, armature 118 and its front contact, front contact and armature 130, lead 50, back contact and armature 271, lead 51, armature 153 and its back contact, armature 167 and its back contact, lead 27, wiper 605 of the primary distributor and the first contact in its bank, winding of magnet 610 of the secondary distributor SD¹, lead 29, winding of relay 233 to battery. In this circuit the battery feed relay 233 is operated and at armature 234 completes a supervisory circuit 25 which will be more fully described later. Moreover magnet 610 is operated and attracts its armature preparatory to advancing the wipers of the switch SD¹ and relay 264 is also operated and at armature 265 completes a circuit for relay 268. This relay at armature 269 completes a circuit for the slow-to-pull-up relay 266 which upon operating in due course, at armature 267 opens the circuit originally traced, whereupon relay 264 and magnet 610 fall back and the latter advances the switch SD¹ one step. Relay 264 upon releasing, opens the circuit of relay 268 and this in turn brings down relay 266 whereupon, unless the operator's position then connected with is in condition to be tested, magnet 610 is again energized and the cycle recommences. The relay 533 in Fig. 6 is used for feeding battery to the operator's headset and when the operator is 30 absent from the position and has therefore withdrawn her headset plug, relay 533 is de-energized and extends earth over armature 534 and lead 408 to the first contact in the bank of the secondary distributor SD¹ over which access is obtained to this position. It will be understood that the battery feed relay of the other operators' positions are connected up similarly to other contacts in the banks of the switches SD¹—SD³. The secondary distributor continues to advance step-by-step owing to the pulses received from relays 264, 266 and 268 until wiper 611 encounters a contact to which earth is connected owing to the operator being absent from the corresponding position. Thereupon the following circuit is completed: earth connected to this contact over the back contact and armature of the battery feed relay, wiper 611, first contact in the bank of wiper 601 and said wiper, lead 24, normally closed springs controlled by 35 armature 105, lead 59, armature 289 and its back contact, lead 60, back contact and armature 160, back contact and armature 145, armature 116 and its front contact, winding of relay 131, lead 56, low resistance upper winding of relay 276, armature 277 and its back contact to battery. Relay 131 is operated in this circuit but not relay 276 in normal working, and the former at armature 132 opens a point in the circuit of relay 270, at armature 40 133 prepares a circuit for the magnet 631 of the junction distributor JD¹, at armature 134 completes a circuit for relays 109 and 152, at armature 135 closes another point in the circuit of relay 180 and at armature 136 disconnects the pulsing earth from the magnet of the secondary distributor SD¹ and extends it to the magnet of the auxiliary secondary distributor ASD¹ over front contact and armature 218, armature 191 and its back contact, lead 2, magnet 647, lead 650, lead 29 to battery through relay 233. Consequently the auxiliary secondary distributor now commences to step and this continues until relay 185 is energized when the auxiliary secondary distributor reaches the same position as its associated secondary distributor. The circuit for relay 185 may be traced from earth, wiper 604 and its first contact, wiper 615, contact in bank corresponding to position of wiper 615, 45 corresponding connecting wire of banks of wipers 615 and 646, to wiper 646, lead 3, armature 219 and its front contact, winding of relay 185 to battery, and the operation of the relay opens the stepping circuit at armature 191. When relay 152 operates, at armature 153 it opens another point in the pulsing circuit to the secondary distributor, at armature 154 prepares a circuit for flashing the indicating lamp by means of relay 274, at armature 155 completes a locking circuit for itself which extends as follows: battery, winding of relay 152, armature 155 and its front contact, normally closed right hand springs of the re-start key RS, armature 169 and its back contact, front contact and armature 123 to earth, at armature 156 opens a point in the circuits of the relays 137, 143 and 162, at armature 157 prepares a circuit for homing the junction distributors, and at 50 55 60 65 70 75 80 85 90 95 100 105 110 115 120 125 130 135 140 145 150 155 160 165 170 175 180 185 190 195 200

armature 158 connects earth from interrupter 92 over lead 54 to relay 274 to flash the position indicating lamp. The operation of relay 185 also at armatures 186—189 and 192 and 193 prepares the connection of the digit and order wire leads over leads 79—82 and 9 and 10 to the wipers of the auxiliary secondary distributor, and at armature 190 completes a circuit for relay 180 extending as follows: battery, winding of relay 180, lead 651, 10 armature 113 and its back contact, lead 652, front contact and armature 190, lead 653, front contact and armature 135, armature 129 and its front contact, front contact and armature 134, armature 169 and its back contact, front contact and armature 123 to earth. Relay 180 upon operating, at armature 181 completes a circuit for relay 229 and this locks up by way of armature 230, at armature 182 completes the following circuit for relay 20 330: battery, winding of relay 330, lead 45, armature 182 and its front contact, lead 38, wiper 502 of the switch TS and the first contact in its bank, lead 453 and by way of interrupter 485 to earth. Moreover at armature 183 earth is connected over lead 44, armature 331 and its back contact, lead 654, upper winding of supervisory relay 314 to battery, and at armature 184 the homing circuit of the 30 test switch TS is opened and earth is connected to wipers 501 and 503. When the contacts of interrupter 485 next close, relay 330 is operated and at armature 331 opens the circuit of the relay 314, at armature 332 opens 35 the circuit of relay 127 and completes a direct circuit for magnet 507 and at armature 333 completes a locking circuit for itself extending as follows: earth, armature 332 and its front contact, lead 441, interrupter contacts 508, lead 429, armature 254 and its back contact, armature 333 and its front contact, winding of relay 330 to battery. The connection of earth to wiper 501 completes a circuit for the first supervisory lamp 542 which 40 lights to indicate that a free position has been found. When magnet 507 has operated fully and opened interrupter contacts 508, relay 330 de-energizes thereby opening the circuit of magnet 507 so that the switch TS is advanced one step. The earth connected to wiper 503 is now extended over lead 440, lead 45, back contact and armature 163, armature 121 and its front contact, front contact and armature 133, lead 655, armature 176 and its 50 back contact, armature 216 and its front contact, lead 20, wiper 613 and the first contact in its bank, lead 656, magnet 631 of the junction distributor JD¹, lead 402, winding of supervisory relay 295 to battery so that magnet 631 is operated. The succeeding pulse from interrupter 485 again operates relay 330 and this in turn effects the advance of the test switch. When the test switch takes its 55 next step and advances to its third position, the circuit just traced is opened and accord-

ingly the wipers of the junction distributor JD¹ are advanced one step. In case the position which has been connected with should only just have been vacated by the operator so that there is a call still in progress over the first junction, there will be earth on the lamp lead and this will accordingly be extended over the appropriate contact in the bank of wiper 625, lead 13, normally closed springs of the fault imitation key 84, lead 74, 70 armature 340 and its back contact, lead 657, upper winding of relay 376 to battery. Moreover owing to the advance of the test switch, the initial circuit over lead 440 is opened and relay 334 is operated over wiper 503 and lead 443. Accordingly the following circuit is now completed: earth, relay 264, armature 267 and its back contact, lead 658, armature 379 and its front contact, lead 659, armature 335 and its front contact, lead 35 and thence over the circuit previously traced to the magnet of the junction distributor JD¹. Consequently this switch is again operated and if one or more further busy junctions are encountered, relay 376 remains operated so that the movement continues until the switch JD¹ has been moved into engagement with a junction over which no call is in progress. Relay 376 will then de-energize and complete a circuit for advancing the test switch which now continues its operation and applies the various tests in turn to this junction as will be fully described subsequently. 80

When wiper 503 has made a complete revolution and again comes into engagement with the second contact in its bank, the circuit traced above again becomes operative for advancing the junction distributor, and in the ordinary course this will take only one step and the next junction will then be connected up for testing purposes. In case, however, this junction should still be in use or should be out of service for any reason, there will be earth on the lamp lead and this will operate relay 376 to step the junction distributor on past this junction as above described. 100

As already pointed out, the switch JD¹ is arranged to deal with 24 junctions, and when its wipers are advanced into engagement with the last of these junctions, the following circuit is completed: earth, wiper 629 and the 24th contact in its bank, lead 12, winding of relay 172 to battery. Relay 172 upon operating, at armature 173 shunts armature 176 and its back contact and at armature 174 completes a circuit for relay 175. The latter upon operating, at armature 178 locks to earth at armature 123, at armature 176 prepares a circuit for the magnet 638 of the junction distributor JD², at armature 177 prepares a circuit for relay 270 and at armature 179 prepares an auxiliary circuit for the magnet of the junction distributor JD². When the testing of this junction has been completed and 110 120 125 130

the test switch again reaches position 2, earth is again connected to lead 440 and is extended to the magnets of both distributors JD^1 and JD^2 , hence JD^1 is advanced to its 25th or normal contact and JD^2 takes one step and tests the first junction in its bank. When the switch JD^1 steps, the circuit of relay 172 is opened and it thereupon releases and prevents any further pulses being sent to magnet 631. If the first junction in the bank of JD^2 is idle and in service the usual tests are carried out thereon and the switch JD^2 is advanced one step to connect up a succeeding junction.

When all the junctions accessible from the bank of the switch JD^2 have been tested, the switch wipers will be advanced to position 23 whereupon a circuit is completed as follows: earth, wiper 636 and the 23rd contact in its bank, lead 11, winding of relay 166 to battery.

Relay 166 upon operating, at armature 167 opens a point in the circuit for stepping the secondary distributor, at armature 168 opens a point in the circuit of relay 270, at armature 169 opens the circuit of relays 109, 152, 175 and 180, at armature 170 closes a point in the circuit of relay 285 and at armature 171 completes a circuit for stepping the junction distributor JD^2 a further step. When relay 180 de-energizes, earth is supplied at armature

184 for homing the test switch and when this reaches normal position, relay 127 is operated. Relay 175 being slow to release holds up for a moment and when it de-energizes the wipers of the switch JD^2 are advanced a further step and the circuit of relay 166 is then opened and it slowly releases. With the wipers of JD^2 in the 24th position, the following circuit is completed: earth, wiper 636 and the 24th contact in its bank, lead 670, first contact in the bank of wiper 612 and said wiper, first contact in the bank of wiper 602 and said wiper, lead 25, armature 154 and its back contact to the lower terminal of the winding of relay 131. Since the original

earth connection to the other terminal of this winding is still intact, relay 131 is now short-circuited and accordingly de-energizes, thereupon at armature 136 again connecting up the pulsing circuit from relay 264 for advancing the secondary distributor. Accordingly conditions are now similar to those obtained when the test was started and the secondary distributor SD^1 hunts to find an idle position. When such a position is found as

indicated by the presence of earth on the associated contact in the bank of wiper 611, relay 131 again operates and at armature 136 completes the circuit for advancing the auxiliary secondary distributor correspondingly. The appropriate junction distributor is then advanced one step and if necessary hunts to find an idle junction on which tests are made as before.

When all the positions accessible from the secondary distributor SD^1 have been tested

or found busy, wiper 615 will be engaging the 21st contact in its bank and a circuit will then be completed as follows: earth, wiper 604 and the first contact in its bank, wiper 615 and the 21st contact in its bank, lead 403, winding of relay 297 to battery. Upon the operation of relay 297 a circuit is completed from earth, armature 124 and its front contact, lead 69, armature 298 and its front contact, lead 68, winding of magnet 607 of the primary distributor, lead 29, winding of relay 233 to battery as before. Magnet 607 thereupon energizes but does not yet advance its associated wipers. Since relay 131 is still not operated, a circuit is again completed for advancing the secondary distributor SD^1 , and wiper 615 accordingly leaves its 21st contact. Consequently the circuit for relay 297 is now opened and it releases, thereby opening the circuit for the magnet 607 of the primary distributor which advances the wipers one step. The secondary distributor SD^2 is thus connected up and the positions accessible over its bank are then tested in the manner previously described. When it arrives at position 21, a circuit is completed for advancing the primary distributor in the same way as above described, and accordingly the secondary distributor SD^3 is brought into action and the unstaffed positions accessible from its banks are duly tested. When all these positions have been dealt with, wiper 621 engages the 21st contact in its bank and a circuit is then prepared for relay 285 but this is not completed owing to the fact that it is held open at armature 231, relay 229 being operated at this time. Consequently the switch SD^3 continues to step in response to pulses from relay 264 until it engages its 23rd contact whereupon a circuit is completed from earth on wiper 604 as before, lead 401, winding of relay 292 to battery. Relay 292 upon operating at armature 293 opens the locking circuit of relay 229 thus causing it to release and at armature 294 extends earth from lead 69 over lead 68 to the magnet 607 of the primary distributor and this is accordingly operated and steps its wipers so as to connect up the secondary distributor SD^1 again, when the above circuit is opened due to the further stepping of the distributor SD^3 .

It has already been pointed out that the tests on an operator's position can only be made when the position is not in use and accordingly it will be clear that even if the routine testing is undertaken at times of light load as would normally be the case, a single operation of the routine would be unlikely to test all the operators' positions. It is therefore provided in the present instance that after all positions have been tested once for busy or idle condition and the idle ones duly routine, the various positions are again tested, only on this occasion not only posi-

tions which are actually busy have to be passed over but also those which have been rousted on the previous operation of the distributing switches. The necessary discrimination is effected due to the position which the second junction distributor takes up when a position has been completely rousted. Reference to Figs. 7 and 8 will show that in this case earth is applied over the 24th contact in the bank of wiper 636 of the junction distributor JD^2 to the contact associated with the position in the bank of wiper 612 and this will have the effect of producing a short circuit on relay 131, so that in the case of positions actually in use no earth is supplied to this relay and in the case of positions which are not in use but which have already been tested earth is supplied to both terminals of the relay so that in either event the relay is unable to operate. Accordingly it does not open the pulsing circuit to the secondary distributor and this switch steps over the position. It will be recalled that when a free position is encountered, relay 131 operates and completes a circuit for relay 180 and this in turn operates relay 229 which locks up dependent upon relays 280 and 292. Hence if all the secondary distributors should pass over the whole of their banks without finding any position in a condition to be tested, relays 131, 180 and 229 will not be operated and in this case when wiper 621 of the secondary distributor SD^3 engages its 21st contact, earth is extended over lead 15, armature 231 and is back contact, lead 65, upper winding of relay 285 to battery. Relay 285 is a two-step relay and at this time only operates its light armature 290 thereby short-circuiting its lower winding by earth on the left-hand contacts of the restart key RS. When the secondary distributor SD^3 receives a further pulse, the initial energizing earth is removed and relay 285 then operates fully over both its windings in series and is accordingly locked up to the re-start key RS. The operation of relay 285 at armature 291 completes a circuit for the routine finished lamp 284 and the lower winding of relay 314 in series and relay 314 operates with results to be described subsequently. Relay 289 moreover at armature 286 opens the normal pulsing circuit for the secondary distributors and auxiliary secondary distributors, at armature 288 opens an auxiliary energizing circuit for itself, at armature 289 opens a point in the circuit of relay 131 and at armature 287 connects earth to wiper 616 of secondary distributor SD^1 . This switch accordingly commences homing and when it has reached its normal position the homing earth is extended to the secondary distributor SD^2 . When this switch in turn has reached its normal position the homing earth is transferred to the switch SD^3 and when this switch has returned to normal a circuit is again completed over lead 407 for

relay 280. Relay 280 upon operating, at armature 281 opens a further point in the locking circuit of relay 229 and at armature 282 opens a point in the magnet alarm circuit.

In case the attendant discovers by operating the key RIK as described subsequently that a number of positions have still not been tested, he may leave the rousting apparatus in this condition for an interval and then by operating the re-start key RS, again set it to hunt for and routine positions which have not yet been dealt with. When the re-start key is pressed, the locking circuit for relay 285 is opened and it releases thereby completing the pulsing circuit for the distributor SD^1 . The operation now proceeds as before and continues until all three distributors again make a complete rotation without finding any position in condition to be tested. It will be noted that in these circumstances only the secondary distributors are restored to normal but not the junction distributors, since these switches indicate by their off-normal position that the associated position has already been tested.

When the start key is restored, on the completion of the test or at any other time the circuit of relay 115 is opened and upon de-energizing it opens the circuit of relay 119. Upon the de-energization of relay 119, a homing circuit for the secondary distributors is completed from earth over armature 120 and its back contact and lead 18 to wiper 616 of the distributor SD^1 whence it is extended in turn to distributors SD^2 and SD^3 . Over armature 123 and its back contact earth is applied over lead 28 to the bank of wiper 606 so that this is effective in bringing about the homing motion of the primary distributor. The earth over the back contact of armature 125 is extended over lead 1 to wiper 630 of the junction distributor JD^1 and serves to effect the homing motion of this switch. When the switch reaches its normal position, the homing earth is extended to the switch JD^2 and this in turn is operated to normal. All the other junction distributors accessible to the rouster are homed in a similar manner, one after the other, and accordingly all the apparatus is left in the position shown ready for a further test to be initiated, for instance the next day. The sole exception is the auxiliary secondary distributors for since they always follow their associated secondary distributors when they are required for use it is unnecessary to return them to a definite normal position. It may be mentioned also that with the arrangement shown, the operation of the key RS is necessary to bring down relay 285, but this could if desired be dependent on relay 115 so that it would release when the start key was restored.

Consideration may now be given to the actual tests which are made on each junction. The initial circuit for stepping the test switch

TS has already been traced, this being completed owing to the operation of relay 330 when relay 180 is energized. It was pointed out, moreover, that with the test switch engaging its second set of bank contacts, a circuit is completed over lead 440 for advancing the first junction distributor of the seized position one step, the test switch meanwhile moving to engage its third set of contacts. In 10 case the junction which is then connected with should have a call in progress or should be out of service, there will be earth on the lamp lead and accordingly the junction distributor will again be advanced under the joint control of relays 334 and 376. When relay 376 deenergizes, a circuit is completed for relay 330 extending as follows: battery, winding of relay 330, lead 45, armature 182 and its front contact, lead 33, wiper 502 and the third contact in its bank, lead 461, back contact and armature 382, lead 671, interrupter 485 to earth, so that the switch TS is moved to fourth position. In this position a circuit is completed over the fourth contact in the bank of wiper 25 503 and lead 446 for relay 336. Upon the operation of relay 336, earth through the lower winding of relay 376 is connected over lead 672, front contact and armature 340, lead 74, normally closed springs of the lamp lead disconnect 30 key 84, lead 13 and over wiper 625 of the switch JD¹ to the lamp lead; if this lead is continuous, battery through the lamp will be operative to energize relay 376. Moreover at armature 337 earth is connected through the winding of relay 389 and over lead 405 and wiper 628 to the positive trunk conductor. In case this trunk should be in contact with any adjacent leads, a circuit will now be completed for relay 389 and it will 35 40 thereupon operate. Furthermore, at armatures 338 and 339 the windings of relay 385 are connected together and over lead 404 and wiper 627 to the negative trunk conductor. The windings of relay 385 are connected in opposition so that if there is no potential on the negative conductor at this time, the relay will not operate but in case the negative line should be in contact with some adjacent leads, relay 385 will be unbalanced and will therefore operate. The condition for a successful 45 50 test is therefore that relay 376 should be operated but that relays 385 and 389 should not be operated. In these circumstances no circuit is completed for the fault indicating lamps 538-540 which are wired to the fourth position of the test switch. It will be seen however that if relay 376 fails to energize, earth on lead 437 will be extended over back contact and armature 378, lead 438, lamp 538, lead 476 and lower winding of relay 314 to battery. Similarly if relay 385 operates a circuit is completed over front contact and armature 386 and lead 436 for lamp 539 and if relay 389 operates lamp 540 is lighted over 55 60 armature 390 and lead 435. A circuit is now completed from the interrupter 485, lead 671, front contact and armature 383, back contact and armature 387, armature 391 and its back contact, lead 462, fourth contact in the bank of wiper 502 and said wiper, lead 33, front contact and armature 182, lead 45, winding of relay 330 to battery. Relay 330 is accordingly operated and effects the advance of the test switch in the manner previously described. With the test switch in 5th position a circuit is completed over lead 427, wiper 503 and lead 447 for relay 341. Upon the operation of relay 341, battery through resistance 399 is connected at armature 342 over lead 673 through relay 389 to the positive trunk conductor and at armature 343 earth through the lower winding of relay 385 and over lead 674 is connected to the negative trunk conductor. Relay 385 only operates if there is battery on the negative line, while the resistance of relay 389 and resistance 399 in series is sufficiently high to prevent the operation of two line relays in parallel if two positive lines should be in contact, but will allow one line relay to operate if there is no contact. Relay 389 is also now operated and the conditions set up by this test are equivalent to the taking of the junction by an "A" operator before it has been assigned. Accordingly if the junction line relay has duly energized, the correct operation at this time is that the junction lamp should be caused to flicker. Hence since relay 336 released when the test switch moved to fifth position the flicker pulses connected to the lamp lead are now transmitted over armature 340 and its back contact to the upper winding of relay 376. Each time relay 376 operates in response to the flicker the following circuit is completed: earth, armature 392 and its front contact, armature 388 and its back contact, armature 384 and its front contact, lead 464, multiplied contacts 5, 6 and 7 in the bank of wiper 502, lead 33, front contact and armature 182, lead 44, winding of relay 330 to battery. The operation of relay 330 as before effects the stepping of the test switch over the next three positions. In each of these positions earth over wiper 501 is extended to the indicating lamp 543. 65 70 75 80 85 90 95 100 105 110 115 120 125 130

When the test switch reaches its 8th position, the circuit of relay 341 is opened and earth is connected over wiper 501 and the multiplied 8th, 9th, 10th and 11th contacts in its bank to the junction assigned indicating lamp 544. The stepping of the test switch over the 8th and 9th contacts is effected by earth from the interrupter 485 being extended over armature 400 and its back contact and lead 454 to the contacts engaged by wiper 502 whence a circuit is completed for relay 330 in the usual manner. While the test switch is in its ninth position, a circuit is completed from earth on wiper 503 to the ninth contact in its bank, lead 444, lead 406

and wiper 626 to the assignment lead associated with the junction. Accordingly the junction is assigned and the sender finder and junction finder at the operator's position are thereupon started up. Since both relays 336 and 341 are now de-energized, both relays 385 and 389 are disconnected and the upper winding of relay 376 is connected as before to the lamp lead. When the sender finder and the junction finder complete their operation, a flash is applied to the lamp, consequently relay 376 will now pulse in synchronism with this flash. Upon each operation of relay 376, earth is connected at armature 377 to lead 434 whence it is extended to the 11th contact in the bank of wiper 502 and serves to operate relay 330 as before. When the test switch reaches position 12, indicating lamp 545 is lighted and a circuit is completed over wiper 503 and lead 448 for relay 344 which accordingly operates. Thereupon at armatures 348-351 it connects wipers 525-528 of the number-set-up switch NS by way of leads 449-452, leads 79-82, armatures 186-189 and leads 5-8 to wipers 641-644 of the auxiliary secondary distributor ASD¹ and at armature 345 completes the following circuit: earth, winding of relay 264, armature 267 and its back contact, armature 345 and its front contact, lead 470, first contact in the bank of wiper 530 and said wiper, winding of magnet 531 to battery. Moreover at armatures 346 and 347 it opens the homing circuit of the number-set-up switch and at the former armature connects the commoning of contacts 2-16 to the pulsing lead from relay 264. Relays 264, 266 and 268 now interact in the manner previously described to send impulses and the switch NS is thus stepped round to effect the setting up of the digit storage relays in the impulse sender, this corresponding to the operation of the digit keys by the operator. It will be understood that the appropriate contacts in the banks of wipers 525-528 of the number-set-up switch are suitably jumpered to earth so as to effect the setting up of the test number which will secure that the test call is routed back to the routiner in a manner which will be more fully described subsequently. When the switch NS reaches its 16th position after having set up a full 7-digit number, a circuit is completed from earth on the 16th contact in the bank of wiper 529, lead 675, 12th contact in the bank of wiper 504, interrupter springs 508, lead 441, back contact and armature 313, lead 439, magnet 507 to battery. Accordingly the magnet is energized and since the above traced circuit includes the interrupter contacts 508, the test switch is advanced one step into the 13th position. In this position the circuit of relay 344 is broken and it de-energizes, thus disconnecting the wipers of the number-set-up switch and completing circuits to cause this to return to normal under the

control of interrupter contacts 532. In the 13th position of the test switch indicating lamp 546 is lighted and a circuit is completed over wiper 503 and lead 456 for relay 352 which upon operating, at armature 356 locks to earth provided at armature 184 of the relay 180. Moreover at armature 354 it connects battery through resistance 399 and relay 389 to the negative trunk conductor and at armature 355 connects earth through the lower winding of relay 385 to the positive trunk conductor. This corresponds to the taking of the junction line by the "A" operator and causes the starting of the sender.

The code digits set up on the storage relay groups in the impulse sender in response to the operation of the number-set-up switch are now sent out, suitably translated so as to cause the routing of the call over a special test level in a selector whence connection is established back to the routiner over the leads 481, 482 and 483. When switching through is effected at the selector, a circuit is completed for relay 367 which extends as follows: from battery, lower winding of relay 367, normally closed springs controlled by armature 359, lead 482, negative trunk conductor, polarized relay in the junction relay set, positive trunk conductor, lead 483, armature 363 and its back contact, normally closed springs controlled by armature 358, upper winding of relay 367 to earth. Relay 367 is accordingly now operated but the polarized relay in the junction relay set does not operate at this time owing to the current flow being in the wrong direction. Upon the operation of relay 367, at armature 368 a circuit is prepared for relay 364 and at armature 369 a circuit is completed for relay 370 and this accordingly operates in turn and at armature 371 prepares a circuit for relay 309. After the junction has been assigned, a steady earth should be applied to the lamp lead and if this condition is duly fulfilled, relay 376 will be held energized over its upper winding. In case, however, any irregularity should have occurred so that flash or flicker pulses are still being applied to the lamp lead, relay 376 will de-energize and will thereupon complete a circuit for relay 309 which locks up and gives the alarm as will be described subsequently. Relay 370 also at armature 372 prepares a circuit for relay 374, while at armature 373 relay 304 is connected to the test conductor 481 extending from the selector level for a purpose which will be described subsequently.

The sending of the numerical digits from the sender will now be initiated and accordingly relay 367 will pulse in response thereto, on each de-energization completing a circuit for relay 374 which owing to its slow characteristic holds up throughout the train. Thereupon at armature 375 earth is connected to the 13th contact in the bank of wiper 502 and when this is removed at the end of

the train of impulses the test switch is advanced one step in the usual manner to the 14th set of contacts whereupon indicating lamp 547 is lighted. The further stepping of 5 the test switch depends on the successful reception of the digits and also on the test which is made by means of relay 304 for guarding earth. The earth for maintaining the connection should be supplied at this time from 10 the junction relay set and is therefore operative to shunt relay 304. If relay 304 remains de-energized, at armature 305 and its back contact earth is applied to the 14th, 15th and 16th contacts in the bank of wiper 502 over 15 armature 375 and accordingly the test switch is advanced through these positions as the various digits are received. When the test switch is advanced to its 14th position after the reception of the first numerical digit, a 20 circuit is completed from the earth on wiper 503 and over lead 460 for relay 357 and this upon operating, at armatures 358 and 359 disconnects relay 367 and connects up in its place relay 523. The battery and earth connections now made to the lines are opposite to those supplied by relay 367 and this is accordingly a test for reversal of the outgoing 25 lines. The operation of relay 523 completes a circuit from earth through the winding of 30 relay 521, armature 524 and its front contact, lead 475, lower winding of relay 367 to battery so that relay 367 is held at this time and accordingly relay 370 also. Impulses now received will therefore cause relay 523 to 35 pulse and the pulses will be repeated at armature 524 to relay 367. This operation only takes place for the reception of the second numerical digit and when this has been successfully completed, the test switch is 40 stepped so that relay 357 is no longer energized. The third and fourth numerical digits are then received in a similar manner and the test switch is accordingly stepped to its 17th position. In this position indicating lamp 45 548 is lighted and the earth on lead 427 is also extended over wiper 503 and lead 465 to relay 360. The operation of relay 360 at armature 363 connects busy flash battery from lead 480 to the positive lead from the selector 50 and at armature 362 connects battery to the earthed winding of relay 367 for the purpose of holding this relay. Moreover at armature 361 contacts 381 of relay 330 are short-circuited so as to prevent undue delay in the 55 operation of the alarm owing to the fact that this test is prolonged for three pulses of busy flash. The application of busy flash battery over the positive lead should result in the repeating back of a corresponding connection 60 from the junction relay set, that is to say the connection of battery to the lead coming into the routine over wiper 627 of the junction distributor JD^1 . Hence since relay 352 is still locked up and therefore armature 355 65 is operated, a circuit is now completed for the lower winding of relay 385. Upon the operation of relay 385, at armature 388 a circuit is completed over wiper 502 of the test switch for relay 330 and when relay 385 releases, this circuit is broken and accordingly 70 the test switch is stepped. In this manner it moves a further three steps and thus advances into its 20th position. A circuit is now completed for indicating lamp 549 and also from earth on wiper 503, by way of the 20th contact in its bank, lead 458, front contact and armature 368 and winding of relay 357 to battery. The operation of relay 357 as before disconnects the windings of relay 367 and connects up instead the windings of relay 523 75 which are reversed in polarity. Accordingly the polarized relay in the junction relay set should now operate and connect up battery to the negative lead in order to give answering supervision to the originating "A" operator. As before relay 523 at armature 524 completes a holding circuit for relay 367 through the winding of relay 521. It will be noted that the circuit for relay 523 includes the contacts of the junction limits key JLK by 80 means of which the shunt and series resistance of the circuit may be altered so as to test the operation of the polarized relay with various limits for the junction resistance. The operation of the polarized relay by connecting battery to the negative lead effects the operation of relay 385 and this as before operates armature 388 though in this case earth is extended over lead 463 to the 20th contact in 85 the bank of wiper 504 and thence over the interrupter contacts 508, lead 441, back contact and armature 313, lead 439, winding of magnet 507 to battery. Accordingly magnet 507 operates and breaks its own circuit at contacts 508 and thus advances the wipers of 90 the test switch into the 21st position whereupon indicating lamp 550 lights. The earth on wiper 503 is now extended over lead 459, winding of relay 364, front contact and armature 368, winding of relay 357 to battery 95 100 whereupon relay 364 operates and relay 357 is maintained operated. At armature 366 relay 364 connects ringing current from the generator G by way of lead 676, armature 325 and its back contact to the positive lead 483 105 whence it is extended over the selectors used and through the condenser in the talking circuit to the corresponding contact in the bank of wiper 628 of the junction distributor JD^1 , lead 405, back contact and armature 324, condenser 484, lead 677, armature 365 and its front contact, lead 678, winding of alternating current relay 393 to earth. If the talking condenser is in proper condition, the 110 ringing current thus transmitted is sufficient 115 to cause the operation of relay 393 and this at armature 394 completes a circuit for relay 328 which at armature 329 in turn energizes relay 326. The operation of armature 327 120 which then takes place is effective to energize 125 130 relay 328.

gize the two-step relay 321 through its first step, whereupon it prepares a locking circuit for itself to lead 69 at armature 322. At the end of the ringing current period, relay 393 releases and accordingly relay 328 and after a short interval relay 326 also releases. Thereupon both windings of relay 321 are connected in series and it operates fully thus at armature 323 opening its own initial energizing circuit and at armatures 324 and 325 transferring the ringing current connection to the negative lead. A circuit may be now traced as follows: earth, generator G, front contact and armature 366, lead 676, armature 325 and its front contact, lead 679, negative conductor 482, through the selectors and the condenser in the negative conductor of the junction relay set, wiper 627 of the junction distributor JD¹, lead 404, front contact and armature 324, condenser 484, lead 677, armature 365 and its front contact, lead 678, winding of relay 393 to battery. When the next period of ringing current starts, relay 393 is again operated and operates relays 328 and 326 as before. Owing to the operation of relay 321 however a circuit is now completed as follows: earth, armature 327 and its front contact, armature 323 and its front contact, lead 477, 21st contact in the bank of wiper 502 and thence to operate relay 330 as before, so that the test switch is advanced to its 22nd position. Indicating lamp 551 now lights and relays 357 and 364 are de-energized and accordingly the current is reversed to its original direction over the junction line and the ringing lead and the alternating current relay 393 are disconnected. Upon the restoration of the current flow to normal, the polarized relay in the junction relay set releases and disconnects the battery feed thereupon releasing relay 385. The following circuit is now completed: earth, armature 392 and its front contact, armature 388 and its back contact, lead 445, 22nd contact in the bank of wiper 504 and said wiper, interrupter springs 508, lead 441, back contact and armature 313, lead 439, winding of magnet 507 to battery. Accordingly the test switch is advanced to its 23rd position, in which position the earth on wiper 503 is extended over lead 457 to short-circuit relay 352 and this after a slight interval releases and at armature 354 disconnects the battery feed through relay 389. Since the line relay of the junction relay set is in series with relay 389, it will also restore at this time and open the junction lamp circuit so that relay 376 should also now restore. Moreover the earth on wiper 501 is now extended to the indicating lamp 541 to indicate the particular test in progress and in parallel to the winding of relay 518. This relay operates and at armature 520 opens the homing circuit of the release timing switch RS and at armature 519 connects up pulses from the interrupter 537 to the two-step relay 515.

Upon the receipt of the first pulse relay 515 operates its light armature 517 and thus prepares a locking circuit for itself which extends over the multiplied contacts in the bank of wiper 512 and said wiper and lead 455 to the release trunk conductor 481 extending from the selector level. On the termination of the pulse, the lower winding of relay 515 is no longer short-circuited and the relay operates fully, thereupon at armature 516 transferring the pulsing circuit to the magnet 513 of the switch RS. This accordingly commences to step and earth is now extended in turn over wiper 509 to the supervisory lamps 552—555 indicating the length of the release interval. As soon as the release trunk conductor becomes unguarded owing to the removal of earth, the locking circuit of relay 515 is opened and it releases, thus stopping the movement of the switch. The permissible time of release is represented by the switch RS stopping on any one of contacts 9, 10 and 11 in which case the circuit of the associated supervisory lamp 554 is completed direct to battery. In case, however, the switch should come to rest either before or after reaching these positions, the associated supervisory lamps 552, 553 and 555 receive their battery over lead 476 through the winding of relay 314 and this operates to initiate the alarm in the usual manner. Furthermore if the switch RS comes to rest before reaching position 9, there will be no circuit completed for advancing the test switch. In case however there is still earth on conductor 481 when wiper 510 reaches the 9th contact in its bank, a circuit is completed from the guarding earth on lead 481, armature 373 and its back contact, lead 466, wiper 510 and the 9th contact in its bank, lead 473, armature 381 and its back contact, lead 472, 23rd contact in the bank of wiper 502 to the winding of relay 330 as previously traced. If this earth is removed while the switch RS is rotating over contacts 9, 10 and 11, the circuit of relay 330 is opened and it brings about the stepping of the test switch in the usual manner. Similarly, if wiper 510 passes clear of the wired contacts, the circuit of relay 330 is again opened and the test switch is stepped. Thereupon the circuit of relay 518 is opened by wiper 501 and the relay releases and at armature 520 completes the homing circuit of the switch RS by way of interrupter contacts 514. The release timing switch is thus restored to normal in readiness for the release test on the next junction. Since the last two contacts in the bank of the homing wiper 506 of the switch TS are permanently connected to earth, this switch now returns to its normal position and relay 127 is again operated. The test switch is now operated in the manner previously described and earth through the interrupter 485 is connected over lead 453 to the first two contacts in the bank of wiper 506.

502. Consequently testing for a free junction now recommences in the manner previously described and when such a junction is found the tests are carried out on it in the 5 same way. When all the junctions accessible over the junction distributor JD^1 have been either tested or found busy, the junction distributor JD^2 is brought into use and tests are made on the junctions accessible from its 10 bank. When these have all been dealt with, another idle position is seized and the junctions associated therewith are rousted.

Consideration may now be given to certain 15 special features concerned with the operation of the routiner. It will sometimes occur that while a position is being rousted the operator returns to it and in this case it is clearly important that the routiner shall not interfere with the normal handling of calls at this 20 position. It is therefore apparent from the fact that all the junction distributors are multiplied together that no junction distributor may be left standing in engagement with a particular junction while some other junction 25 is being rousted. Hence if the operator returns to the position, the junction distributor wipers must be moved clear as soon as possible. If they move to the 24th contacts, the position will be marked as completely 30 rousted when in fact it was not, while if they are moved to the normal position the whole routine test has to be done again. It is conceivable that this might happen several times and consequently that the routiner 35 would test certain junctions a number of times and this would delay the rousting of other operators' positions. To meet this possible difficulty a so-called routine suspense feature has been introduced in the present 40 arrangement according to which if the operator takes up the position again while it is being rousted the rousting operation is held up for a certain period, for instance 3 minutes, and if the operator should vacate 45 the position again during this period the rousting is continued from the point at which it was stopped. In case, however, the position is still busy at the end of the time interval, the routiner is advanced to the next position 50 and the position partly tested is tested again from the beginning at the next opportunity. Upon the operation of relay 131 when a free position is connected with, a circuit is completed for relay 109 as follows: 55 earth, armature 123 and its front contact, back contact and armature 169, armature 134 and its front contact, winding of relay 109 to battery. Relay 109 thereupon at armatures 110 and 111 prepares circuits for the two-step 60 relay 101, whereby earth from the normally closed contacts of the operator's battery feed relay is now connected over lead 24, armature 106 and its back contact, armature 110 and its front contact, upper winding of relay 65 101 to battery, whereupon relay 101 operates

its light armature 104 thereby connecting its lower winding to earth at armature 111. If the position remains free throughout the test, no further changes take place and the relays 101 and 109 are returned to normal when relay 131 de-energizes on the completion of the test of the position. If however the operator should insert her plug during the test, earth would be removed from lead 24 and, accordingly, the lower winding of relay 101 70 would no longer be short-circuited and it would operate fully. Thereupon, at armature 102 it connects earth to lead 13 to light the supervisory lamp associated with the junction with which the routiner is then connected to warn the operator not to use this junction, at armature 103 completes a circuit for the relay 112, at armature 105 completes a locking circuit for relay 131, at armature 106 prepares a circuit for relay 258, and at 75 armatures 107 and 108 prepares circuits for two-step relay 261. Relay 112 at armature 114 locks up over its lower winding to earth at the back contact of armature 332, and at armature 113 opens the circuit of relay 180 80 which accordingly de-energizes, thereupon at armature 184 completing a homing circuit for the test switch so that this accordingly restores to normal. When normal position is reached relay 127 is again operated and the locking circuit of relay 121 is accordingly 85 opened at armature 128, but relay 121 remains operated over its initial energizing circuit. 90

Consider first the case in which the operator has arrived for a full spell of duty. The first complete pulse from the 3-minute interrupter 91 will operate relay 261 over lead 42 and this at armature 262 will transfer the pulse lead to relay 258, hence when the next pulse arrives, relay 258 is operated. 100 Thereupon at armature 259 it completes a momentary additional circuit for relay 112 over lead 40 and at armature 260 opens the locking circuit of relay 101 and completes a circuit for the lower winding of relay 251. 105 Relay 251 operates momentarily but since no locking circuit is completed for its upper winding at this time it releases when relay 258 falls away shortly after the end of the pulse. Upon the release of relay 101 the locking earth for relay 131 is removed and this releases, but relay 152 is locked up for the present. Accordingly the following circuit is now completed for homing the junction distributor JD^1 assuming that this is 110 at present in action: earth, relay 264, armature 267 and its back contact, lead 47, armature 148 and its back contact, lead 61, back contact and armature 286, lead 62, armature 157 and its front contact, back contact and armature 133, lead 655, armature 176 and its back contact, armature 216 and its front contact, lead 20, wiper 613 of the distributor SD^1 , magnet 631 to battery through relay 120 233 as usual. Accordingly JD^1 is advanced 125 130

and when it reaches its 24th position, relays 172 and 175 are operated to connect up the magnet of the distributor JD^2 . When this reaches its 23rd position, relay 166 is energized and a circuit is then completed from earth, normally closed left-hand contacts of the quick routine key QR, front contact and armature 168, lead 680, armature 177 and its front contact, lead 681, back contact and armature 132, lead 49, winding of relay 270 to battery. Relay 270 now operates, at armature 273 locks up independent of relay 175, at armature 271 opens the circuit of the secondary distributors and at armature 272 prepares a circuit for the magnet of the junction distributor JD^2 . Relay 166 opens the locking circuit of relay 175 as usual and when the latter releases, the switch JD^2 is advanced to 24th position. Thereupon relay 166 is de-energized and when it releases, a circuit is completed over back contact and armature 171 for advancing the switch JD^2 to 25th or normal position. This circuit is opened at armature 272 when relay 270 releases owing to the opening of its circuit at armature 168 and JD^2 is thus restored to normal. Moreover since relay 270 has now released armature 271 and relay 152 has released armature 153, the circuit for the secondary distributors is again completed and an idle position is hunted for in the usual manner. The position which the operator has taken up is now marked as untested and is fully routined when next it becomes free.

Consider now the case in which the operator again vacates the position before relay 258 has been operated from interrupter 91. When the operator withdraws her plug, earth is again connected to lead 24 and is extended over armature 106 and its front contact and lead 41 to relay 258, which operates with the results previously described. In this case however when relay 101 de-energizes, relay 131 is maintained operated by earth on lead 24 and hence no circuit is completed for homing the junction distributors. Moreover, as relay 131 is operated a locking circuit is completed for the upper winding of relay 251 extending as follows: battery, upper winding of relay 251, front contact and armature 253, armature 256 and its back contact, lead 37, front contact and armature 135, armature 129 and its front contact, front contact and armature 134, armature 169 and its back contact, front contact and armature 123 to earth. Relay 180 is operated again as soon as relay 112 de-energizes and then prepares the test switch for further operation. Relay 251 in addition to completing a locking circuit for itself at armature 253, at armature 254 opens a point in the locking circuit of relay 330, and at armature 252 extends earth from armature 184 over lead 426 to wiper 504 and thence to magnet 507 of the test switch by way of its interrupter contacts

508. The test switch is thus advanced to position 4, in which battery through magnet 507 is extended over wiper 504 and the fourth contact in its bank and lead 428 to earth through relay 255. Magnet 507 does not now operate but relay 255 does and at armatures 256 and 257 brings down relay 251 thus permitting the normal test operation to start on the trunk which the routiner was engaging when operation was interrupted. This arrangement therefore ensures that each position shall be fully tested but tends to prevent certain junctions of one position being tested a number of times and thus delay in the testing of other positions.

The routine indicating key RIK is provided to enable a ready indication to be obtained of the number of positions which have been dealt with. It will be seen that when this key is operated battery is connected to lead 14 in place of the normal earth and is extended through the various position indicating lamps to the 24th contacts in the banks of wipers such as 636 of the various second junction distributors. In case the positions have been dealt with, these wipers will be standing on the 24th contact and thus an earth will be supplied for lighting the lamps. As already mentioned, the indicating lamp associated with the position which is actually being tested is normally flashed in the circuit extending from battery, back contact and armature 277, upper winding of relay 276, armature 275 and its back contact, lead 55, front contact and armature 154, lead 25, wiper 602 of the primary distributor wiper 612 of the secondary distributor SD¹, lamp such as 608, lead 14, normally closed contacts of the routine indicating key RIK to earth. Hence when the key is operated, this lamp will be extinguished though this is of little importance and the lamps associated with all the positions which have already been routined, will be lighted. By this means the attendant can readily ascertain at any time the exact progress of the test.

The release alarm key RA is provided in order to enable the alarm to be disconnected after a fault has been found. It will be seen that earth is provided over the normally closed contacts of this key and lead 72 to lock up the alarm relay 309 which is operated as shortly to be described when a fault is found.

The re-start key RS enables the testing operation to be re-started after it has been stopped due to the distributors making a complete revolution without finding any positions idle and untested. At the left-hand springs of this key earth is then removed from lead 34 so as to open the locking circuit of the routine finished relay 285 while at the right-hand springs a point in the locking circuit of relay 152 is opened; consequently conditions are again restored for enabling the distributors to make a further test for posi-

tions which are idle and have not yet been dealt with.

It may be desirable in some cases to perform a continuous routine test upon a certain position or also upon a certain trunk particularly in case a fault has originally been encountered and it is now desired to see that it has been properly cleared. For a continuous routine test of a particular position, the key PCR is operated before the start key SK and the former at its left-hand springs completes a circuit for relay 119 which operates and performs the functions previously described. At the right-hand springs of the key PCR, a circuit is completed from earth, armature 117 and its back contact, back contact and armature 156, right-hand springs of key PCR, winding of relay 137 to battery. Upon operating, relay 137 at armature 138 prepares a circuit for relay 270, at armature 139 connects earth to the stepping keys, at armature 140 opens a point in the homing circuit of the secondary distributors, at armature 141 prepares a circuit for relay 285 and at armature 142 completes a locking circuit for itself. The group stepping key GS is now operated to move the primary distributor wipers into engagement with the required secondary distributor, the circuit extending from earth, front contact and armature 139, springs of key GS, lead 68, winding of magnet 607 to battery over lead 29 to the winding of relay 233. Then the position stepping key PS is operated and each time its contacts close a circuit is completed from earth at armature 139, contacts of key PS, lead 27, wiper 605 to magnet 610 and thence to battery through relay 233 as before. When the required position has been connected with as indicated by the lighting of the corresponding lamp, the start key is thrown and upon the operation of the start relay 115, the circuit of relay 131 is completed at armature 116 and at armature 118 a circuit (which will not become effective in this case) is prepared for stepping the secondary distributor. Upon the operation of relay 131, the test proceeds in the manner previously described on the particular position selected. When all the junctions accessible over the first junction distributor have been routined, relays 172 and 175 are operated as previously described and relay 175 serves to transfer the stepping circuit to the second junction distributor and locks up over its own armature 178. When all the junctions accessible from the bank of the second junction distributor have been tested, relay 166 is operated as before and opens the circuit of relay 175 at armature 169. While relay 175 holds up, however, a circuit is completed from earth, armature 179 and its front contact, front contact and armature 170, armature 141 and its front contact, lead 64, back contact and armature 288, upper winding of relay 285 to battery. Relay 285 being of the two-step type operates its light armature 290 at this time, thereby short-circuiting its lower winding over lead 34 and the left-hand contacts of the re-start key. Moreover a circuit is now completed from normally closed left-hand contacts of the key QR, front contact and armature 168, lead 680, armature 177 and its front contact, lead 681, armature 138 and its front contact, lead 49, winding of relay 270 to battery. Relay 270 thereupon locks up at armature 273, at armature 271 opens another point in the stepping circuit for advancing the secondary distributor and at armature 272 prepares a circuit for the magnet of the second junction distributor. When relay 175 releases after its slow period the circuit of the junction distributor magnet is opened and it accordingly steps the associated wipers thereby opening the circuit of relay 166 which also releases after a slight interval thus opening the circuit of relay 270. Moreover at armature 170 the shunt earth is removed from the lower winding of relay 285 and it now operates fully thereby lighting the routine finished lamp and performing the other functions previously described. When relay 166 de-energizes and while relay 270 still holds up, earth on lead 52 is extended over back contact and armature 171 to advance the junction distributor a further step to normal position. If it is desired to make a further test on the junctions in this position, the re-start key is operated whereupon at the left-hand contacts of this key the locking circuit of relay 285 is opened and the previous conditions are restored. Otherwise the attendant will restore the keys PCR and SK whereupon homing circuits are completed for the primary and secondary distributors as previously described and these switches restored to normal.

In case it is desired to make a continuous routine test on a particular trunk, the key TCR is operated instead of the key PCR. Thereupon at the left-hand contacts of this key a circuit is completed for relay 119 as before, while at the right-hand contacts earth from the back contact of armature 117 is extended to the winding of relay 162. Relay 162 upon operating, at armature 163 opens the pulsing circuit for the junction distributor so that this shall not be advanced at the end of each test, at armature 164 applies earth to the stepping keys and at armature 165 completes a locking circuit for itself. In addition to the keys GS and PS, it will be necessary in this case to operate also the key TS which completes a circuit which is readily traceable for the magnet of the proper junction distributor. This test will continue on the trunk selected until the start key or the key TCR is restored.

In order to facilitate the location of faults, the key FL is provided and when this is operated a circuit is completed for relay 110 as

before and also relay 143 is operated. This at armature 144 supplies earth to the stepping keys in the usual manner and opens the circuit of the visible alarms, at armature 145 6 opens a point in the circuit of relay 131, at armature 146 prepares a circuit for relay 180, at armature 147 completes a locking circuit for itself, at armature 148 prepares a stepping circuit for the auxiliary secondary distributor since as relay 131 will not be operated 10 in this case no circuit is completed by it, at armatures 149 and 150 prepares connections over the auxiliary secondary distributor to the order wires extending to the position 15 in question and at armature 151 removes earth from the second group of multiplied contacts in the bank of wiper 506 of the test switch. Since relay 180 is not yet operated in this case, this means that tests will start 20 at position 13 of the test switch owing to the homing earth remaining connected to the first group of multiplied contacts. The attendant may now if he wishes by operating the appropriate stepping keys set the distributing switches on to any desired junction at any position and then operate the start key and observe from the supervisory lamps the progress of each test. When the test switch has rotated to position 13, relay 180 25 is operated over wiper 505 and the test then proceeds in the normal manner. It will be noted that when the attendant is locating faults, since relay 131 does not have to be operated, he may make connection with a 30 position which is staffed, and may if he wishes throw the order wire key OWK and order up a connection from the operator over a particular junction. It will be seen that when the order wire key is thrown the transmitter and receiver of a hand set 89 specially provided on the routiner are connected up to leads 76 and 77 and thence through the repeating coil windings to the upper and lower windings of the relay 395. This relay 35 accordingly operates and at armature 396 connects up the other windings of the repeating coil in a circuit including leads 75 and 78 armatures 149 and 150, 192 and 193 and leads 9 and 10 to wipers 639 and 640 40 of the auxiliary secondary distributor ASD¹. Moreover, at armature 397 a point is opened in the auxiliary circuit for relay 180 and at armature 398 a circuit is completed for advancing the test switch to its thirteenth 45 position. The attendant will then release the key OWK thus deenergizing relay 395, which at armature 397 permits relay 180 to operate and completes a circuit for the order wire supervisory lamp 90 thus indicating to the 50 attendant that the test has commenced.

It has already been mentioned that the junction limits key JLK serves as a means for testing the limits of operation of the polarized relay in the junction relay set. The 55 function of the fault imitation keys 84-88

will be clear without detailed description. It will be seen that these provide a ready means of testing the correctness of operation of the routiner itself since when one of these keys is operated the corresponding fault would 70 show up on the particular junction then under test even though this is in fact in perfect order. The keys shown provide for the imitation of the following faults, no earth on lamp lead, battery or earth on negative lead, or battery or earth on positive lead. It will 75 be seen that the provision of these keys is quite important since the routiner itself is a complicated piece of apparatus and may possibly therefore be almost as liable to faults 80 as the apparatus it is designed to test, and these keys provide a simple means of obtaining a check on the operation of the routiner itself.

A description will now be given of a feature 85 which may be advantageous in some cases. It will be seen from reference to the Passmore application mentioned, that there are four sets of common apparatus which can be associated with the operator's position and since the switch termed the outlet finder advances one step for each call set up, if routine tests are to be made on all the common apparatus only four junctions at the position need to be tested. Moreover, as previously pointed out, 90 with the arrangement shown the capacity of the two junction distributors is 46 junctions and it is not desirable to provide more than two of these distributors. In case, however, there should be 50 junctions incoming to the position, the remaining four can conveniently be dealt with over contacts 1-4 of the first junction distributor, the changeover from junctions 1-4 to junctions 47-50 being made 95 by suitable relays. In the present instance the positions are assumed to be equipped with 50 junctions and accordingly the quick routine test is made over junctions 47-50. For this purpose the quick routine key QR is thrown, whereupon at the right-hand contacts 100 of this key a circuit is prepared for relay 159 and a point is opened in the circuit of relay 270. Moreover, at the left-hand springs of the key QR, earth is extended over lead 70, winding of relay 299, lead 71, armature 194 and its front contact, lead 4, wiper 645, lead 409, winding of relay 536 and winding of relay 535 to battery. The relays 535 and 536 105 it will be understood are associated with the particular position and may conveniently be mounted adjacent to the battery feed relay 533; relay 299, however, is located in the routiner and serves for all the positions. Upon the operation of relays 535 and 536 the leads 110 from the first four contacts in the banks of wipers 625-628 are transferred to the lamp, assignment and positive and negative conductors of junctions 47-50. Moreover at armatures 300-303 of relay 299 the indicating 115 lamp leads from the first four contacts in the 120

125

130

135

banks of all the distributors JD¹ are transferred so as to connect up the indicating lamps connected with junctions 47—50 instead of those associated with junctions 1—4.

5 The test now proceeds in the usual way upon the operation of the start key and when junctions 47—50 have been rousted a circuit is completed over wiper 629 in 5th position, lead 83, right-hand contacts of key QR, lower 10 winding of relay 159 to battery. Relay 159 upon operating, at armature 161 locks up over its upper winding and at armature 160 brings down relay 131. The junction distributors are then moved to the "position rousted" contacts, that is, the 24th position of the second junction distributor, and the operation of relay 166 brings down relays 152 and 159 and allows testing to take place for the next free position on which the quick routine test is made in similar manner. Hence it is possible by this means to make a quick routine test which will test all the common equipment at the operator's position and also junctions 47—50 and will only occupy a fraction 25 of the time required for the full test. It will be appreciated that in the case of positions equipped with 50 junctions, in order to test all the junctions it will first be necessary to make the full routine test which will deal 30 with junctions 1—46 and subsequently to make the quick routine test which will then deal with junctions 47—50.

The arrangements for giving an alarm may now be briefly dealt with. It will be appreciated 35 that the advance of the test switch to initiate a test is dependent on the success of the previous test and that if the test switch remains in any position except its normal one for more than a predetermined interval, the 40 alarm will be given. A circuit may be completed for the lower winding of the alarm relay 309 over armature 377 in case the junction lamp does not receive full earth, as previously mentioned but in general relay 309 45 will be operated after a time interval under the control of relays 306 and 314. When relay 314 is operated, at armature 317 it connects an additional earth to the motor start lead 490 and at armature 315 connects up in- 50 terrupter 316 to relay 306 and at armature 320 prepares a locking circuit for this relay. Relay 306 first operates its light armature 308 and subsequently also armature 307 thereby transferring the pulses to relay 309. If 55 the conditions persist, relay 309 operates in due course locks up to the key RA at armature 312, at armature 313 opens the circuit of magnet 507 to prevent the test switch moving, at armature 310 lights an alarm lamp as- 60 suming relay 143 is not operated, and at armature 318 connects up an alarm bell. It will be seen that the circuit prepared for the upper winding of relay 314 at armature 183 is opened by relay 330 each time that relay op- 65 erates to step the test switch. The normally

energized relays 278 and 280 associated respectively with the junction distributors and the primary and secondary distributors serve to supervise the operation of the magnets of these switches. In the case of the primary and secondary distributors, battery feed is through relay 233 and this at armature 234 connects earth to lead 58 and hence through lamp 283' to relay 314. Similarly battery feed relay 295 at armature 296 supplies earth 70 through lamp 283. When the start key is restored, earth is connected over armature 123 to lead 57 and should relays 278 and 280 not operate in due course, relay 314 would again be operated and the alarm be given so 75 that supervision is obtained of the return of the switches to normal. The routine finished lamp 284 also obtains its battery from relay 314 so that an alarm is given in case the attendant does not at once notice the lighting 80 of the lamp. Moreover the various fault indicating lamps obtain battery over lead 476 from relay 314 so that these also may be instrumental in giving the alarm.

It will be understood that armatures 90 196—204 of relay 195 and 206—214 of relay 205 are wired to the auxiliary secondary distributors ASD² and ASD³ in the same way as the corresponding armatures of relay 185 are wired to the auxiliary secondary distributor 95 ASD¹. It may be mentioned also that relay 276 is provided to perform the functions of a fuse. In normal operation, the current flowing through the low resistance upper winding of relay 276 is not enough to effect its 100 operation, but in case an abnormal current demand arises, relay 276 operates, and at armature 277 cuts in its lower winding which is of comparatively high resistance, so as to reduce the current to safe limits.

What I claim as new and desire to secure by Letters Patent is:

1. In a telephone system, automatic routine testing equipment for testing telephone apparatus, means for associating said testing equipment with said telephone apparatus, means for testing idle ones of said apparatus, and means responsive to the taking into use of any one of said pieces, for halting the testing operations for a predetermined interval 110 of time.

2. In a telephone system, a plurality of groups of telephone apparatus, automatic routine testing equipment, means for associating said equipment with one of said groups, means for testing the individual pieces of the telephone apparatus of said group, means responsive to the taking into service of any one of the pieces in said group for halting the testing operations for a predetermined interval of time, said halting means effective if said piece of apparatus is released from service within said time period 120 for causing the resumption of said testing operations.

3. In a telephone system, a plurality of groups of telephone apparatus, automatic routine testing equipment, means for associating said equipment with one of said groups, means for testing the individual pieces of the telephone apparatus of said group, means responsive to the taking into service of any one of the pieces in said group for halting the testing operations for a predetermined interval of time, said halting means effective if said piece of apparatus is released from service within said time period for causing the resumption of said testing operations, and means effective if said piece of apparatus is not released from service within said time period to operate said associating means to associate said equipment with another group of apparatus.

4. In a telephone system, a plurality of operator's positions, each having a plurality of similar pieces of telephone apparatus thereat, automatic routine testing equipment, means for associating said equipment with a vacant one of said positions, means in said equipment for testing the pieces of apparatus thereat, means effective upon the occupation of said position during testing for halting the testing operations for a predetermined interval of time, said halting means effective if said position is again vacated within said time period for causing the resumption of said testing operations, and means operable at the end of said time period provided said position has not been vacated for operating said associating means to associate said equipment with another vacant position.

5. In a telephone system, a plurality of operator's positions, each having a plurality of similar pieces of telephone apparatus thereat, automatic routine testing equipment, means for associating said equipment with a vacant one of said positions, means in said equipment for testing the pieces of apparatus thereat, means effective upon the occupation of said position during testing for halting the testing operations for a predetermined interval of time, said halting means effective if said position is again vacated within said time period for causing the resumption of said testing operations, means operable at the end of said time period provided said position has not been vacated, for operating said associating means to associate said equipment with another vacant position, and means for subsequently causing said associating means to re-associate said equipment with the said position occupied during testing but vacated after the expiration of said time period.

6. In testimony whereof I have signed my name at Liverpool, England, this 20th day of April, 1928.

LANCELOT MARTIN SIMPSON.
